LIGHTER CASING STRUCTURE

James Donald Smith, Stroudsburg, Pa., assignor to Ronson Corporation, Woodbridge, N.J., a corporation of New Jersey

Filed Jan. 6, 1960, Ser. No. 785

4 Claims. (Cl. 67—7.1)

In one of its aspects the invention relates to a cigar lighter casing which serves as the main support for the working parts of the lighter and also acts as a confining wall for the fuel contained in the lighter, the primary objective being a structure satisfactory for such purposes which will enable the same to be constructed of extruded aluminum without entailing parts which would render unduly difficult the production of the casing by known impact extrusion technique. In this aspect the invention has particular advantage as applied to lighters of the butane type wherein the wall structure surrounding the fuel chamber should be of high strength because of the radically higher internal fluid pressures entailed in lighters fueled by butane gas and the like as compared to lighters fueled by so called lighter fluid in liquid form. This requirement of high strength has heretofore led in lighters of the butane type, to the use of casings of objectionably heavy weight. A casing constructed in accordance with the present invention, due to the superior strength vs. weight characteristics of extruded aluminum as compared to lighter casings previously used for such purposes, enables a marked reduction in weight to be secured while still maintaining adequate strength in the surrounding wall of the fuel chamber when charged with a normal amount of fuel of the butane type even when the lighter is subjected to tropical temperature conditions. A reduction in weight may be thereby readily obtained, amounting to about $\frac{1}{3}$ in comparison with lighter casing structures previously used for the reception of fuels of the butane type, which is especially advantageous in pocket lighters. Also the cost of the casing structure is substantially reduced, on the same basis of comparison. Such a casing constructed of extruded aluminum is also advantageous in lighters irrespective of the type of fuel employed, in that the material is compatible with so called anodizing treatments, in contrast for example with die-cast lighter casings as heretofore used. This enables desirable finished surface effects to be obtained by such anodizing treatment which are not possible, for example, with die-cast lighter casings as heretofore used. Such die-cast lighter casings also have not had sufficient strength to serve satisfactorily under the fluid pressures obtaining in lighters of the butane type. Accessory elements, as hereinafter described more in detail, for mounting the working parts of the lighter on the casing, may be provided as unitary integral parts of the main casing, incidental to the formation of the casing by impact extrusion, also without rendering the operation unduly difficult.

In another aspect the invention involves a windshield structure used as a protection for the flame of the lighter, which is adapted in construction for use in connection with a lighter casing of the type above referred to, this windshield structure having advantages in respect to the effective admixture of air with the gases to be ignited when the lighter is actuated, to promote reliable ignition. Further objects and advantages of the invention will be in part obvious and in part referred to in the description hereinafter contained which taken in conjunction with the accompanying drawings, discloses a preferred form of lighter casing constructed to function in accordance with the invention; the disclosure however should be considered as merely illustrative of the invention in its broader aspects. In the drawings:

2

FIG. 1 is a central vertical sectional view taken through a preferred form of lighter casing constructed in accordance with the invention, the casing being shown prior to the assembly therewith of the various operating parts constituting the complete lighter, and with its accompanying bottom wall plate shown separately.

FIG. 2 is a side elevation with certain parts cut away, showing the lighter casing of FIG. 1 in assembled relation with various working parts of a complete lighter.

10 FIG. 3 is a view similar to FIG. 1, but showing the lighter casing in its initial as extruded condition.

15 FIG. 4 is a detail sectional view taken on lines 4—4 of FIG. 2 looking in the direction of the arrows, but with the closure cap, sparking wheel, and fingerpiece of the lighter removed.

The invention is shown as applied to a lighter having a main casing provided with a top wall 1 from the peripheral portions of which an enclosing side wall 2 depends. From the top wall 1 a pair of spaced ears 3 extend upwardly to constitute a support for a sparking wheel and certain other working parts of the lighter as hereinafter described in greater detail. Also a flange 4 preferably extends upwardly from top wall 1 to serve as a fingerpiece guard as later set forth in more detail. 20 Preferably the flange 4 merges at its extremities into the side of the ears 3, both of the above parts being in the nature of upward extensions of the side wall 2, as shown in FIG. 2. The top wall 1 of the casing may also be provided with a post 5 which extends down into the 25 interior of the casing and also preferably projects somewhat above the top wall.

30 The above described casing and appurtenant parts constitute a structure which may be satisfactorily formed as a unitary product by a single operation comprising 35 the cold impact extrusion of aluminum, an aluminum base alloy relatively high in tensile strength being preferably employed for reasons already stated, the parts entering into the casing structure being of a configuration and so correlated that special techniques in connection with the extrusion are not required.

40 FIG. 3 shows the casing structure in its initial "as extruded" condition, the side wall 2 having an extended annular lip 2a which is cut off as indicated by 45 the dotted line 2b (FIG. 3). Then as indicated in FIG. 45 1, the top wall 1 of the casing is tapped out to provide a threaded hole 6 for the reception of a burner valve structure, and a further threaded hole 7 for the reception of a flint tube, the ears 3 being provided with holes 7a 50 to receive a stud 21 which carries the sparking wheel of the lighter, and the post 5 being bored out as shown in FIG. 1 to receive the plunger of the fingerpiece of the lighter.

55 The space within the casing serves as a fluid tight fuel chamber 8, the bottom of which is closed by a bottom wall member 9 which also is preferably constructed of extruded aluminum or aluminum base alloy. This bottom wall member 9 is shown as provided with a peripheral flange 10 (FIG. 1) which seats against the rim at the bottom of side wall 2, the annular side wall 11 of member 9 fitting closely within the bottom portion of side wall 2, and the joint between the members 2 and 9 being preferably sealed by a synthetic resin of the heat-setting type. The bottom wall member 9 may be provided with a threaded hole 12 for the reception of a fuel charging valve, and a further opening 13 for the reception of a flint tube.

60 In FIG. 2 a fuel charging valve 14 is shown as mounted in the threaded hole 12, and this valve may be understood as of a type appropriate for injecting butane or 65 like fuel into chamber 8. Since valves appropriate for such purposes are known in the art, the valve 14 will not

be described in detail. This valve may be for example as shown in FIGS. 1-3 of the U.S. patent to Conrad Zellweger No. 2,832,940 issued April 21, 1959.

FIG. 2 also shows a flint tube 15 having its upper portion in threaded engagement with the hole 7 previously mentioned, and its lower end 16 headed over to seat against the wall of opening 13. The parts within the flint tube may be understood as conforming to usual practice in the art, and hence are neither shown nor described.

A burner valve structure 17 (FIG. 2) may also be understood as mounted in the threaded hole 6 in top wall 1, the burner being of a construction appropriate for use in connection with butane type fuel, for example as shown in FIG. 4 of the U.S. patent to Conrad Zellweger No. 2,836,044. In FIG. 3 this burner valve structure is shown as provided with an angularly movable flame height adjusting member 18 which may be understood as corresponding with the member 12 of the above mentioned Zellweger patent, the burner having an outlet opening 19 into the space immediately above the flame height adjusting member 18.

In FIG. 2 I have shown the sparkling wheel 20 carried by a stud 21 supported in the holes 7a of ears 3. This stud also mounts pivotally a closure cap 22 which in the closed position shown in FIG. 2, holds the burner valve closed. A depressible fingerpiece 23 is also shown in FIG. 2 as having a stem 24 which fits slidably within the post 5 to guide the movements of the fingerpiece, the latter being articulated to the closure cap 22 and sparkling wheel 20 in such manner that manual depression of the fingerpiece swings the closure cap up to open position and turns the sparkling wheel 20 to project sparks into the path of gaseous fuel issuing from the outlet opening 19 of the burner structure. Since appropriate forms of working parts for such purposes are known in the art, they are not shown or described in more detail herein.

To promote the reliable ignition of gaseous fuel issuing from the outlet opening 19 of the burner I have shown in FIGS. 2 and 4 a windshield member 25 which is preferably of U shape and positioned to partially enclose the space above the burner outlet opening 19, and also partially enclose the closure cap 22 when the latter is closed. The lower portions of this windshield member are spaced above the flame height adjusting member 18 in such manner as to provide a space 26 which largely surrounds the zone immediately above flame height adjusting member 18. When the closure cap 22 is swung to open position, at which time the sparkling wheel 20 causes sparks to be projected into the zone under discussion, a stream of air passes radially inward so to speak through the space 26 into admixture with the gaseous fuel issuing from opening 19, thereby effecting a substantially uniform combustible mixture of air and gaseous fuel, in a manner to promote more reliable ignition. The end portions of the windshield member 25 are provided with tabs 25a (FIG. 4), through which the stud 21 passes, and by which the windshield member is supported in the position shown in FIG. 2, resting against the adjacent side walls of the upwardly extending ears 3.

While the invention has been disclosed as embodied in a lighter structure of the above described specific form, it should be understood that changes may be made therein without departing from the invention in its broader aspects, within the scope of the appended claims.

I claim:

1. A pyrophoric lighter having a unitary fuel casing constructed of a single piece of extruded aluminum formed by an impact extrusion operation, said casing comprising a top wall and an enclosing side wall formed integrally therewith and extending downwardly from the peripheral portions of said top wall, and a separate bottom wall member glued to the bottom portion of said side wall to provide a sealed fuel chamber within said casing structure.

2. A pyrophoric lighter having a unitary fuel casing constructed of a single piece of extruded aluminum formed by an impact extrusion operation, said casing comprising a top wall and an enclosing side wall formed integrally therewith and extending downwardly from the peripheral portions of said top wall, a separate bottom wall member glued to the bottom portion of said side wall to provide a sealed fuel chamber within said casing structure, spaced ears extending upwardly from said top wall to constitute sparking wheel supporting members, and a post extending downwardly from said top wall within said casing to constitute a fingerpiece support, said ears and post being formed integrally with said casing.

3. A pyrophoric gas lighter having a unitary fuel casing adapted to hold fuel under pressure and constructed of a single piece of extruded aluminum formed by an impact extrusion operation, said casing comprising a top wall and an enclosing side wall formed integrally therewith and extending downwardly from the peripheral portions of said top wall, spaced ears extending upwardly from said top wall to constitute sparking wheel supporting members, and a post extending downwardly from said top wall within said casing to constitute a fingerpiece support, said ears and post being formed integrally with said casing, a burner valve carried by and extending from said top wall and having a fuel outlet opening therein, a flame height adjusting member overlying said top wall adjacent said burner valve, a windshield member, means supporting said windshield member above said flame height adjusting member and partially surrounding said burner valve, said windshield member being spaced above said flame height adjusting member to afford the flow of air to the interior of said windshield member adjacent said outlet opening, and a separate bottom wall member glued to the bottom portion of said side wall to provide a sealed fuel chamber within said casing structure.

4. A pyrophoric gas lighter having a unitary fuel casing adapted to hold fuel under pressure and constructed of a single piece of extruded aluminum formed by an impact extrusion operation, said casing comprising a top wall and an enclosing side wall formed integrally therewith and extending downwardly from the peripheral portions of said top wall, spaced ears extending upwardly from said top wall to constitute sparking wheel supporting members, and a post extending downwardly from said top wall within said casing to constitute a fingerpiece support, said ears and post being formed integrally with said casing, a burner valve carried by and extending from said top wall and having a fuel outlet opening therein, an angularly movable flame height adjusting member overlying said top wall adjacent said burner valve, a U-shaped windshield member, means supporting said windshield member above said flame height adjusting member and partially surrounding said burner valve, said windshield member being spaced above said flame height adjusting member to afford the flow of air to the interior of said windshield member adjacent said outlet opening, and a separate bottom wall member glued to the bottom portion of said side wall to provide a sealed fuel chamber within said casing structure.
